UNITED STATES PATENT OFFICE.

HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING APPARATUS.

Application filed October 9, 1926. Serial No. 140,450.

My invention relates to railway signaling apparatus and particularly to apparatus of the type comprising railway signals located in the trackway for governing the passage 5 of railway vehicles. More particularly my present invention relates to apparatus for controlling railway signals of the type usually designated as slotted electric signals, that is, signals of the type comprising an 10 operating mechanism made up of a driving motor for moving the signal from its normal or de-energized position to a second position in which latter position the signal is held by a slot mechanism, the driving motor 15 being disconnected when the signal reaches its operated position.

I will describe one form of railway signaling apparatus embodying my invention, and will then point out the novel features 20 thereof in claims.

The accompanying drawing is a diagrammatic view illustrating one form of railway signaling apparatus embodying my invention.

25 Referring to the drawing, the reference characters 1 and 1^a designate the track rails of a stretch of railway track over which traffic normally moves in the direction indicated by the arrow. These track rails are 30 divided by means of insulated joints 2 into a plurality of successive track sections, only one of which, A—B, is shown complete in the drawing. Traffic over the stretch of track shown in the drawing is governed by 35 trackway signals each designated by the reference character S with an exponent corresponding to the location, and in the form here shown each signal is of the three-position semaphore type capable of indicating proceed, caution or stop. Each signal is located adjacent the entrance end of the corresponding section. It should be understood, of course, that this particular arrangement and construction of the signals S is not 40 essential to my invention. For controlling the signal S^A, section A—B is provided with a polarized direct current track relay R connected across the rails adjacent the entrance end of the section. Track circuit current is 45 supplied to the rails of section A—B from a battery K connected across the rails adjacent the exit end of the section. The polarity of the track circuit current supplied to the rails of the section A—B by the battery K

is controlled by a pole-changer P operatively 55 connected with signal S^B, and arranged to occupy one position when the signal indicates caution or proceed and to occupy the other position when the signal indicates stop. 60

It should be pointed out that while I have shown only section A—B provided with a track circuit including a track battery A, a pole-changer P, and a track relay R, each of the remaining sections are provided with 65 similar apparatus.

The operating mechanism of signal S^A is at times supplied with energy from a suitable source such as a battery D. When signal S^B indicates stop, the relative polarity of 70 the current supplied to relay R is such that the polar contact 3 of the relay is open, but the front contacts 21 and 22 are closed. Under these conditions, current flows from battery D, over wire 4, front contact 21 of relay 75 R, wires 5 and 6, operating mechanism of signal S^A, wires 7 and 8, front contact 22 of relay R, and wire 9, back to battery D. When this circuit is closed, the signal S^A displays a caution indication. When signal 80 S^B indicates proceed or caution, however, pole-changer P is reversed and the polarity of the current supplied to relay R is then such that relay R closes its polar contact 3. Under these conditions the caution circuit 85 just traced is closed and in addition a proceed circuit is closed from battery D, through wire 4, front contact 21 of relay R, wires 5 and 10, polar contact 3 of relay R, wire 11, operating mechanism of signal S^A, wires 7 90 and 8, front contact 22 of relay R, and wire 9 back to battery D. When this circuit is closed, signal S^A displays a proceed indication. When section A—B is occupied by a 95 train, relay R becomes de-energized, interrupting both the proceed circuit and the caution circuit for signal S^A and causing that signal to indicate stop.

Polarized direct current relays of the type 100 commonly used in railway signaling systems are so constructed that when the polarity of the current supplied to the relay is reversed, the relay first opens its front contacts, next reverses the polarized armature, and finally recloses the front contacts. With relays 105 constructed in this manner it will be apparent that should signal S^A be at caution or proceed and should pole-changer P be re-

versed, the neutral front contacts of relay R would be open for a brief interval of time during the reversal in the direction of energization of relay R. During this brief interval of time, the circuit or circuits for the operating mechanism of signal S^A would be interrupted and it might happen that this interval of time could be long enough to permit the slot mechanism of the signal to release and allow the signal to return to the stop indication.

I therefore provide a transformer T having a primary 19 and a secondary 20. The primary 19 of this transformer is provided with a circuit which may be traced from battery D, through wire 12, a circuit controller J operated by signal S^A, wire 13, primary 19 of transformer T, wire 14, back contact 22 of relay R, and wire 9 back to battery D. The circuit controller J is arranged to be closed only when signal S^A indicates caution or proceed, and the primary circuit for transformer T is therefore closed only when relay R becomes de-energized with signal S^A at caution or proceed. The secondary 20 of transformer T is provided with a circuit which passes from the right-hand terminal of this secondary, through wire 15, back contact 21 of relay R, to wire 5 and thence through wire 6 (or through wire 10, polar contact 3 and wire 11) to the operating mechanism of signal S^A, returning through wires 7 and 16 to the left-hand terminal of secondary 20 of transformer T.

To explain the operation of the apparatus I will assume that the relay R is energized in the reverse direction so that polar contact 3 is open; signal S^A then indicates caution and circuit controller J is closed. I will now further assume that relay R opens its front contact and closes its back contacts for a brief interval of time. For example, this could happen if pole-changer P became reversed as by the movement of signal S^B from stop to caution. The closing of back contact 22 of relay R completes the circuit for primary 19 of transformer T. A surge of current is therefore supplied to primary 19 from battery D. As a result of the increasing current in the primary 19 an electromotive force is induced in secondary 20 which supplies current to the operating mechanism of the signal over back contact 21 of relay R in the same direction as the current which is normally supplied to the operating mechanism from battery D. Of course the current supplied to the operating mechanism of the signal by the secondary of transformer T is only a surge and this current ceases as soon as the current in the primary of transformer has attained a steady value, but I have discovered that in actual practice this surge of current is sufficient to maintain the slot mechanism in its energized condition and

to prevent the release of the signal during brief interruptions of the operating circuit for the signal resulting from temporary opening of the front contacts of relay R.

In order to prevent arcing at back contact 22, I connect a rectifier 17 of any suitable type in parallel with the primary 19 of transformer T. The rectifier is so disposed as to offer its higher resistance to current supplied to the primary from battery D. When back contact 22 is opened, however, to interrupt the circuit for primary 19, the energy stored in the magnetic field surrounding the primary tends to force a current through the rectifier 17 in its lower resistance direction. As a result of this connection then, the energy of the magnetic field is dissipated through the rectifier 17 and the formation of a destructive arc is prevented at back contact 22. For a similar purpose a second rectifier 18 is connected in parallel with the secondary 20 of transformer T to prevent arcing at back contact 21 of relay R.

Although I have herein shown and described only one form of railway signaling apparatus embodying my invention, it is understood that various changes and modifications may be made therein within the scope of the appended claims without departing from the spirit and scope of my invention.

Having thus described my invention, what I claim is:

1. In combination with a railway signal having the usual operating mechanism, a circuit for said mechanism, means for at times interrupting such circuit for a brief interval, and means for supplying a surge of energy to the mechanism during such interval.

2. In combination with a railway signal having the usual operating mechanism, a relay, means for at times energizing the relay, means effective when the relay is energized to supply energy continuously to the operating mechanism of the signal, and means effective when the relay becomes de-energized to supply the mechanism with a surge of energy.

3. In combination, a railway signal, a relay controlled in accordance with traffic conditions, a circuit for the operating mechanism of the signal including a source of energy and a front contact of the relay, a transformer having its primary connected with the source over a back contact of the relay, and a second circuit for the operating mechanism of the signal including the secondary of the transformer and a back contact of the relay.

4. In combination, a railway signal, a relay controlled in accordance with traffic conditions, a circuit for the operating mecha-

nism of the relay including a source of energy and a front contact of the relay, a transformer having its primary connected with the source over a back contact of the relay, a second circuit for the operating mechanism of the signal including the secondary of the transformer and a back contact of the relay, and a rectifier connected in parallel with one winding of the transformer to prevent arcing at the back contacts of the relay.

5. In combination with a railway signal, a relay, a circuit for the operating mechanism of the signal including a front contact 15 of the relay, and means effective when the relay becomes de-energized with the signal in its operated position to supply a surge of energy to said operating mechanism.

6. The combination, with a railway signal, 20 a polarized relay, a caution circuit for the operating mechanism of the signal in-

cluding a front contact of the relay and a source of direct current, and a proceed circuit for such mechanism including a front contact and a polar contact of the relay and 25 said source, of a transformer having its primary connected with the source through a back contact of the relay, and means including a back contact of the relay for supplying energy from the secondary of the 30 transformer to the operating mechanism of the signal.

7. In combination, a railway signal, a first circuit including the signal and at times including a source of energy, a second circuit including a source of energy, and means for transferring energy from the second circuit to the first circuit for a brief interval when the source of energy is disconnected from the first circuit. 35 40

In testimony whereof I affix my signature.
HERBERT A. WALLACE.
